UNITED STATES PATENT OFFICE.

FRED A. JENKS, OF PLYMOUTH, MASSACHUSETTS, ASSIGNOR TO PLYMOUTH CORDAGE COMPANY, OF NORTH PLYMOUTH, MASSACHUSETTS, A CORPORATION OF MASSACHUSETTS.

LABEL FOR ROPE.

Application filed February 8, 1927. Serial No. 166,782.

This invention relates to improvements in labels for rope. More particularly it has to do with the labeling of rope by incorporation in the rope structure of identifying 5 elements of foreign material which may bear a printed inscription.

The impracticability of satisfactorily marking a hemp or wire rope, by printing or otherwise marking clearly or durably on 10 its surface, and the inescapable similarity of one rope to another, when made of similar material, makes it highly desirable to be able to identify a particular rope as being of certain material, or as being the product 15 of a particular manufacturer. A label for the purpose of giving such information must not interfere with the use of the rope; and it should be so protected and preserved that it will serve its intended purpose, even after 20 a rope has seen years of service.

The invention provides such a label by the use of discontinuous flexible strips, of distinctive aspect and of inexpensive material, preferably printed, adapted to be 25 distributed at suitable intervals throughout the rope. An important feature resides in the means whereby these labels are secured to a yarn of the rope, at distances apart, before the yarn is, with others, made 30 into the rope. They may be considerably broader than the yarn, and yet, by being wrapped helically around it, be incorporated smoothly in the rope. In a finished rope the labels are for the most part protected 35 against the friction and wear to which the rope may be subjected; and although made of cheap materials, they will be available at all times through the life of the rope, with their print sufficiently preserved to be legible.

40 The invention proposes to use relatively short, thin, flexible strips of paper or more durable sheet composition in the nature of paper, leather, etc., of a desired distinctive aspect, and to secure them in spaced relation 45 on a yarn by means of a single thread or filament wound helically about the yarn from end to end. The labels may be laid lengthwise on the yarn or they may be wrapped helically around it, but in all cases 50 they are bound thereto on the surface thereof by the convolutions of the thread. When a yarn prepared with labels is made into a rope with other yarns, which may or may not be marked in like manner, the labels

become for the most part embedded in the 55 rope structure; and as the yarn with which they are associated is a part of the rope, enduring in its environment as long as the rope endures, the labels, although not a part of the yarn, are nevertheless equally available 60 at all times, being protected and preserved with their yarn, provided only that they are made of durable materials. The small filament which binds them may disappear utterly under friction of use and lapse 65 of time, and the above mentioned materials of which the strips are composed being limp are inherently incapable of maintaining themselves in any particular position, so that the label might be expected also to disappear; but in the greater number of cases, excepting only those where the label has 70 happened to come to rest on the surface as the rope is made, the label remains bound by compression between its environing yarns of 75 the rope, to which it was introduced while bound by the filament, and can always be found by unlaying a few inches of rope. A permanent and highly satisfactory means for distinguishing rope may thus be provided 80 with a minimum of material; and this material available in suitable quantities at small cost.

It is intended that the patent shall cover, by suitable expression in the appended 85 claims, whatever features of patentable novelty exist in the invention disclosed.

In the accompanying drawings:

Figure 1 is an elevation of a length of rope embodying the invention, somewhat diagrammatic and enlarged for clearer showing; and

Figures 2 and 3 show likewise a yarn of rope illustrating how labels may be arranged and secured thereon before the yarn, with 90 others, is made into a rope.

Referring to the drawings, a piece of rope, 10, has a series of distinctive strips 12, which may be of paper, composition, leather or other inexpensive, flexible, durable sheet material, embedded in the rope structure at suitable intervals along it. The composition may be, for example, viscose, vellumoid, a treated paper composition or other composition of cellulose or its derivatives, chosen 95 with qualities of thinness, toughness, durability and printability, and for power to resist the oil, water, friction and other de-

teriorating influences found in rope. Each strip 12 may be a complete label in itself, with the name or trade mark of the manufacturer on it, the date of manufacture, or other printed information, or the strips may be so distinctive in design, without printed matter, that each will serve as a means of conveying the desired information about the rope. According to the invention a multiplicity of the labels 12 are distributed periodically along a yarn 14 before the rope is made, and preferably they are arranged flatwise against its surface, along it or wrapped around it helically and they are temporarily secured to the yarn by a filament 16 of any suitable sort which may be wound or braided from end to end of the yarn with its convolutions passing over the strips and binding them upon the surface of the yarn. This filament may be a thread of textile material, or may be a cellulosic product or other continuous form which is by machinery of suitable type wound around the yarn while the yarn is being drawn forward, and while the labels are being in succession fed to its surface at the place where the filament is passing to position on the yarn. For this purpose either the yarn or the filament supply may be the rotating member, or both may rotate, turning in opposite directions, while the strips are fed from suitable stationary mechanism, or from a source turning with the turning of the yarn. In the latter case the strip would be laid straight along the axis of the yarn as indicated in Figure 1, as also it would be if neither yarn nor strip were turning while the filament were being wound. In Figure 2 the label 20 is wrapped helically about the yarn 14' in direction opposite to that of the filament 16'; and at 18 in Figure 3 the strip is wrapped about the yarn 14'' in direction of the wind of the thread 16''. This helical sort of wrapping makes it possible that the label be relatively broad, as compared with the size of yarn, if such be desired. In all cases, however, each label is a short strip disconnected from all like strips and securely held on the yarn, without protruding beyond the general surface of the yarn. When a yarn thus marked is embodied with others in a rope, the strips thereon become embedded in the rope structure (except as one may occasionally appear with the yarn at the surface) and, for the most part, will be protected and concealed. Each will then be securely held in the rope by pressure of surrounding yarns, and thus will not be materially affected by the breaking or wearing away of the filament 16 or 16' when the rope is in service. The label is particularly useful for wire rope, being in that case embodied in the vegetable fibre centre rope of the wire rope; and in that event the few labels which appear at the surface of the

fibre rope are nevertheless entirely within and concealed and protected by the wires of the wire rope. The appearance at the surface may moreover be in some cases considered rather an advantage than a disadvantage, in that the occasional exposed labels will serve to identify a new rope without need for delving into the rope structure; and yet the majority of the labels will be within the rope, protected and preserved, to identify rope which has been in use, perhaps for a number of years. Because light and thin materials are employed any portions thereof exposed on the rope surface ordinarily may be worn away during use of the rope, and before that they will in no way hinder or interfere with the use of the rope. The invention provides simple and inexpensive means for labeling ropes. It includes labels at the surface for identification of new ropes, and labels within the rope structure which will be preserved until such time as the identity of a used rope is called in question. The labels themselves may show any information which it is desired to associate permanently with the rope. The helical wrapping and binding holds the labels smoothly on the surface of the yarn, so that all the yarns together can be laid smoothly in thin regulation formation; the thickness of a label is not so great as to disturb the strand formation; and the color of the label indicated for example as being red in Figure 1, contrasting with the color of the fibre from which the yarns are made, makes the labels easily discernible. In the drawing the size of yarns relative to rope is considerably exaggerated, but it will be understood that dimensions may be selected according to desire. The binding filament may be made mildly adhesive in character, just before applying it, thus tending to prevent slipping displacement of filament or label, even though both be applied loosely. If preferred the convolutions of filament may be closer together than illustrated; or there may be added a filament wound in the opposite direction, or two or more such may be braided over the yarn, in each case enclosing the label on its surface.

The term "flatwise" as herein used refers to an arrangement in which the label is not twisted upon its own axis before being applied to the yarn, but has one of its originally flat surfaces lying more or less smoothly against, and curved with, the curved surface of the yarn.

An adequate labelling of a rope can be accomplished without having the labels as close together along a yarn, as the limitations of a drawing had made it advisable to represent them in Figure 1, and without so large a proportion of them appearing at the surface.

I claim as my invention:

1. The combination, with a rope, of a label

therefor comprising a thin, flexible sheet on a yarn of the rope structure; and a filament wound about said yarn with its convolutions passing over said label and binding it to the said yarn.

2. The combination, with a rope, of a label therefor comprising a thin, flexible sheet on a yarn of the rope structure; and a filamentary enclosure about said yarn and label, 10 binding the label to the yarn.

3. The combination, with a rope, of means associating information therewith comprising a multiplicity of discontinuous, thin, flexible strips of sheet material distributed 15 at intervals along a yarn within a strand of the rope; and a filamentary enclosure about said yarn binding said strips thereon.

4. The combination, with a rope, of means associating information therewith comprising a multiplicity of discontinuous, thin, flexible strips wound helically around a yarn of the rope structure at intervals throughout 20 its length and therewith embedded within a strand of the rope.

25 5. The combination, with a rope, of means associating information therewith comprising a multiplicity of discontinuous, thin, flexible strips wound helically around a yarn of the rope structure at intervals throughout 30 its length, and a filament wound about said

yarn and strips in direction reverse of that of said strips, binding said strips thereon.

6. In the manufacture of rope, an intermediate product for associating information with a rope, comprising a yarn; a thin, flexible label on the yarn; and a filamentary enclosure about the yarn, enclosing said label and binding it to said yarn. 35

7. A method of marking rope comprising the preliminary securing of a series of thin, 40 flexible strips at intervals along a yarn by a filamentary enclosure of at least temporary strength; and thereafter laying said yarn and its enclosure, with other yarns, into a rope, whereby said strips become permanent- 45 ly held by being embedded in the rope structure.

8. The combination, with a rope, of means associating information therewith comprising a multiplicity of discontinuous, thin, 50 flexible strips arranged at intervals on and extending along a yarn of the rope structure, lying wholly on the surface of the yarn, made of limp material embedded with the yarn in the rope and held in said position by compression between yarns of the rope. 55

Signed at Plymouth, Massachusetts, this first day of February 1927.

FRED A. JENKS.
